RADIO-ACTIVITY LOGGING OF WELLS

John T. Hayward, Tulsa, Okla.

Application September 19, 1947, Serial No. 774,945

10 Claims. (Cl. 255—1.8)

1

The present invention is directed to logging wells drilled by the rotary method in which a circulating stream of fluid is used for removal of the cuttings and, in particular, to the logging of such wells by measuring the radioactivity of the formations traversed.

Methods for logging wells have already been proposed in which measurement of the radioactivity of a formation traversed by the bore hole is made. The method commonly employed is one in which a Geiger-Muller counter is lowered into the hole. This method has the limitation that in order to prepare a log of the well, drilling must be suspended and the tools withdrawn from the hole. As this is a lengthy operation and involves expensive delays, the radioactivity survey is usually postponed until several thousand feet of hole have already been drilled. The present method is directed toward giving a log that is continuously current during the drilling and without interfering in any manner with the progress of the drilling operation.

Methods for logging wells by radioactivity and utilizing the mud stream have also been proposed and involve measurement of the radioactivity of the flowing mud stream by placing some sort of radiation detector, such as a Geiger-Muller counter or an ionization chamber, in or adjacent to the mud stream. Attempts along these lines have proven generally unsuccessful in practice for the following reasons: The circulating fluid is composed of water which may comprise 50 to 80 per cent of the fluid and which is obtained from various sources, such as surface supply wells, and which may of itself have considerable radioactivity. In addition, the mud fluid contains various materials that are added to it at the surface in order to give it the weight and viscosity suitable for proper drilling. These materials generally consist of finely divided bentonitic shales, barytes and other mud heavies, etc., the natural radioactivity of which is usually considerably in excess of the formations being drilled and these materials usually comprise 5 to 20 per cent by weight of the circulating fluid. In addition, the mud fluid contains finely ground material obtained from the action of the bit on formations higher up the hole and which have been circulated numbers of times around the system. These materials also may comprise up to 20 percent by weight of the circulating fluid. Lastly, the circulating fluid as it issues from the hole carries with it cuttings made by the bit in pulverizing the core actually being drilled. These cuttings seldom amount to as much as one

2

per cent by weight of the fluid. It will be seen, therefore, that upon measurement of the total radioactivity of the mud stream or any unclassified portion thereof, variations in the radioactivity of a formation actually being drilled, since they will only affect less than one percent of the stream, will be entirely masked by the non-significant radioactivity of the rest of the stream.

The principal object of the present invention is to obtain a log of the well as it is being drilled by measuring the radioactivity of only that part of the material carried by the stream which was added to it in its last passage past the bit and which consists of an actual sample of the

15 formation drilled and dispersed in the mud stream as the bit pulverizes the core being drilled. In order to accomplish this, the circulating fluid issuing from the well is continuously screened. The mesh of the screen is so chosen 20 that the materials added at the surface to condition the mud will easily pass through it and only the coarser portions of the core drilled up by the bit, the so-called cuttings, will be retained upon it.

25 It will be obvious that if the total stream is passed through the screen before it enters the well, any material retained upon the screen must have been picked up on the last journey through the well. Mechanical vibrating screens 30 are readily available for the extraction of these cuttings. As an alternative to the screen, or shale-shaker, a large settling pit can be used. In such a pit the velocity of the fluid is low and ample time is available for the deposition of the

35 cuttings. In this case also, therefore, the coarser pieces in the issuing mud must have been picked up during the last trip and if some fraction of the issuing stream is then screened in a device such as that discussed later, material retained 40 in it must have come from the formation drilled when the corresponding increment of mud passed the bit.

An additional object of the present invention is to provide a method and apparatus for the production at the top of a bore hole during the drilling thereof of a log of the radioactivity of the formations traversed by the bore hole.

Further objects and advantages of the present invention will become apparent from the following detailed description when read in conjunction with the accompanying drawings which illustrate several embodiments of apparatus which may be employed for successfully practicing the logging method in accordance with this invention.

In the drawings:

Referring to Fig. 1, there is shown, more or less diagrammatically, the top of a well including a well casing 10 having a side outlet 11 near its upper end. The usual hollow drill pipe 12, carrying a drill bit (not shown) at its lower end, extends into casing 10 and it will be understood that drilling fluid 13 is circulated in the conventional manner down through the interior of drill pipe 12 to the bottom of the well where it passes through the usual openings in the head of the bit into the annular space between the drill pipe and the wall of the well. As drilling fluid 13 passes the bit it receives the cuttings being currently cut from the formation being drilled by the bit and carries these cuttings upwardly through said annular space and out of the well through side outlet 11. The stream of drilling fluid containing the cuttings is discharged from outlet 11 and passed in its entirety through a sloping screen 14 of the conventional vibrating type, commonly known in oil field parlance as a "shale shaker." The mesh of screen 14 is selected to pass all of the mud fluid except cuttings of the desired size, the latter being caught on the upper surface of the screen which, by virtue of its slope and vibratory movement, will continuously discharge these cuttings, indicated at 15, from off the lower end thereof and cause them to collect in a suitable receptacle 16 positioned below the lower end of the screen. The cuttings 15 thus collected in receptacle 16 are thereby made available for further handling in the manner to be described hereinafter. The drilling fluid passing through screen 14 after removal of cuttings 15 is discharged into a trough 17 through which the fluid is discharged to a conventional suction pit (not shown) from which the fluid is picked up by mud pumps and returned to drill pipe 12 to complete the cycle in the usual manner. The stream of drilling fluid thus returned to the well, will, of course, be free of the cuttings removed by the screen so that the next group of cuttings carried by the next increment of the exiting drilling fluid stream which will be caught on the screen will represent a succeeding increment of the formations being traversed by the bit.

The cuttings thus separated from successive increments of the drilling fluid and collected in receptacle 16 may be continuously related to the earth formations or strata from which they came in accordance with the method described in detail in Hayward U. S. Patent No. 2,214,674, September 10, 1940. In this manner, the subsequently described tests performed upon the cuttings samples may be related to the depths of the parent formations or strata for constructing the desired log of the well. The aforementioned Hayward patent describes a method for continuously correlating the successive increments of the drilling fluid and the contained core fluids with the depths of the originating strata and since the solid cuttings normally do not travel up the bore hole at exactly the same rate as the fluid, a correction factor must be introduced, preferably by the use of a so-called "tell-tale." Such a tell-tale generally consists of pieces of solid matter which are chosen so as to resemble the cuttings as nearly as possible both as to size and density. The tell-tale is inserted in the drill pipe and the number of pump strokes required to cause its re-arrival at the surface noted, the tell-tale particles being caught on the shaker screen along with the cuttings.

From this number, a calculated number of pump strokes to cause the tell-tale to travel from the surface to the bit is deducted. It has been found in calculating this number that it may be safely assumed that the cuttings and the fluid move downwardly in the drill pipe at the same velocity. The time of travel from the surface to the bit in any case is only a small part of the total time for the complete circuit. Broken pieces of tile and colored concrete have been found to be very suitable materials for tell-tales.

Reference may now be made to Fig. 2 which represents a form of apparatus suitable for manual operation in performing the step of determining the natural radioactivity of the cuttings collected in receptacle 16. A cylindrical container 18, which may be made of, for instance, brass, has removably installed in it a tubular wire mesh screen 19. A radiation detector 20, which may be of the conventional Geiger-Muller or ionization chamber type is concentrically inserted in wire screen 19. This radiation detector is connected to a preamplifier 21, frequency meter 22, and an indicator 23, all of which are of conventional construction, the details of which are well known and form no part of the present invention. Cuttings 15, obtained from receptacle 16, are inserted in the annular space between the screen 19 and the walls of the container 18. The screen serves to protect the walls of the radiation detector which are purposely made thin in order to be transparent, particularly to beta radiation, which is the type of radiation most easily and efficiently detected. The counts shown by the frequency meter over a predetermined period of time, for example, in one-half to two minutes, are characteristic of the sample in the container and the figure so obtained is related to the formation to which it corresponds by the methods disclosed in the aforesaid Hayward Patent No. 2,214,674, modified in the manner previously noted.

By thus measuring the natural radioactivity of samples of the cuttings as they are continuously separated from successive increments of the drilling fluid leaving the well, a continuous log of the well may be made in terms of the radioactivity of the successive strata penetrated by the drill without interference with the drilling operation and the operator may thus be continuously informed of the nature of the strata being currently penetrated by the drill.

Since, as noted previously, the entire stream of drilling fluid is continuously screened as it leaves the well and all of the cuttings larger than the selected mesh of the screen are removed from the fluid before it is returned to the well, the cuttings will, in every case, represent only the formations being currently cut by the drill bit, and the radioactivity log constructed therefrom in the manner described will accurately represent the currently traversed earth strata and will be free of error arising from the inclusion in the test samples of any extraneous or non-significant material, in any manner otherwise introduced into the stream of circulating drilling fluid.

Fig. 3 and 4 illustrate a form of apparatus which may be used for performance of the method in accordance with this invention in cases where no shale shakers are available at the well site. In this embodiment, side outlet pipe 11 has connected to its underside a short length of perforated pipe, forming a tubular trap 24, having the perforations in its wall covered by a screen 25 of a mesh suitable for retaining

within the trap cuttings of the desired size. A low baffle or weir 26 is positioned on the bottom of outlet pipe 11 on the downstream side of trap 24 transversely to the path of flow of drilling fluid 13 and serves to slow the velocity of the drilling fluid as it passes over the mouth of trap 24. A sloping trough or mud ditch 27 is positioned below trap 24 and the outer end of outlet pipe 11 to receive the drilling fluid discharge from either or both of these exits. The lower end of trap 24 is provided with a flap valve 28, hinged at one side, as at 29, for opening and closing the bottom of trap 24. Opening and closing movements of flap valve 28 are controlled by means of an electric motor 30 which is connected to an operating extension 31 of the flap valve by means of a conventional worm-gear and quadrant mechanism indicated by the numeral 32. Flap valve 28 has mounted therein a radiation detector 33 of the well known Geiger-Muller or ionization chamber type, having its detection face extending above the upper surface of flap valve 28 into the interior of trap 24. Leads 34 extend from the radiation detector for connection to the usual radiation amplifying and indicating system such as that shown diagrammatically in Fig. 2. A pair of leads 35-35 connect motor 30 to a program clock mechanism 36, of any suitable and conventional design, which is supplied with alternating current from a suitable source indicated at 37. A pair of electrical contacts 38 and 39 are mounted in the bottom of trough 27 and spaced slightly apart vertically for purposes to be later described. Contact 38 is connected to ground and contact 39 is connected by a lead 40 in series with a battery 41 and the coil 42 of a relay, indicated generally by the numeral 43, and thence to ground. Armature 44 of relay 43 is connected by a lead 45 to program clock mechanism 36 and has connected thereto a suitable source of alternating current 46. An electrical contact 47 arranged for contact by armature 44 is connected by a lead 48 to program clock mechanism 36.

The embodiment illustrated in Figs. 3 and 4, as described above, is operated in the following manner for logging a well in the terms of the radioactivity of the cuttings. With flap valve 28 in the closed position shown in Fig. 3, cuttings will drop out of the fluid flowing over the top of trap 24 and will be trapped and held therein by screen 25, the screened fluid passing through the screened perforations in the wall of trap 24 and discharging into trough 27 where it rejoins the major portion of the fluid stream discharging further down the trough from the end of outlet pipe 11. As the cuttings accumulate in trap 24, they gradually close off successively higher perforations in the trap wall until all of the perforations have been sealed off, whereupon the flow of screened fluid into trough 27 from the trap will cease. The cessation of flow into the upper end of the trough lowers the level of liquid flowing therein sufficiently to break the fluid connection between contacts 38 and 39. The breaking of this contact closes relay 43 which will cause program clock mechanism 36 to start a new cycle. After a period of time, depending upon the type of radiation detector used, the clock operated mechanism will start motor 30, which opens flap valve 28 and discharges the cuttings deposited in trap 24 on the face of the flap valve and above and about the detector face of the radiation detector 33 into trough 27. Fluid from the stream passing through outlet pipe 11

will, of course, follow the cuttings and wash them completely from the face of the flap valve and of the radiation detector. After a suitable interval necessary to accomplish this operation, the mechanism of program clock mechanism 36 will cause motor 30 to reverse and close flap valve 28 in order that a new group of cuttings may deposit in trap 24, to begin a new test cycle.

During the interval between the breaking of the circuit at contacts 38 and 39 and starting of motor 30 by program clock mechanism 36, radiation detector 33 will, of course, be receiving the radiations from the cuttings in the trap and will transmit this indication to the indicating or recording apparatus connected to the detector. The quantity or increment of the mud stream from which the group of cuttings thus examined are deposited will be correlated with the depth of the formation from which the cuttings came in the manner previously described in connection with the embodiment of Figs. 1 and 2. By repeating the operation described, the radiation characteristics of the cuttings of successive increments of the drilling fluid may be determined and a continuous log made of the formations. The mud fluid leaving trough 27 flows to a conventional settling pit of relatively large area in which the cuttings will have sufficient time to settle out so that cuttings-free liquid will be returned by the mud pumps in the usual manner to the well and again, as in the previously described embodiment, the cuttings appearing in trap 24 will represent the cuttings from the formations being currently cut by the bit.

Fig. 5 illustrates another embodiment of apparatus by which a continuous log of the radioactivity of the cuttings may be obtained automatically. A modified form of Geiger-Muller counter, indicated generally by the numeral 50, comprises a generally cylindrical chamber 51, constructed of some suitable material such as brass, which has extending axially therethrough, a tube 52 which serves as a radiation window, and is, constructed of very thin metal, or other suitable material of well known character designed to readily pass radiations into the interior of chamber 51. The lower end of tube 52 is open and the upper end is provided with funnel-shaped mouth 53. The interior of tube 52 is concentrically lined with a screen 54, slightly spaced therefrom to protect the normally fragile tube from being torn or punctured by the cuttings particles from which radiations are received. Tube 52 and chamber 51 form the usual anode 55 of the counter. The cathode comprises a plurality of thin wires 54a concentrically disposed between the wall of chamber 51 and the exterior of tube 52 and vertically suspended from a ring-shaped conductor support 55. The anode (chamber 51 and tube 52) and the cathode (wires 54a) are connected through leads 56 and 57, respectively, and a conventional electrical circuit to an amplifier 58 which is connected by leads 59, 60 to a conventional frequency meter 61, the output of which drives the pen arm 62 of a conventional strip chart recorder 63. A normally open switch 64 is interposed in lead 59 and is controlled by a relay 65 which is, in turn, controlled by a program clock mechanism 66 of well known design driven from a suitable source of A. C. 74. Disposed on opposite sides of mouth 53 of tube 52 is a light source 67 and a cooperating photo-electric cell 68. The latter is suitably and conventionally connected to an amplifier 69, the output of which actuates a relay 70 which controls a normally open

switch 71, the contacts of which are connected by leads 72, 73 to program clock mechanism 66. Alternating current source 74 is connected into lead 72.

The lower end of tube 52 is closed by a conical plug valve 75 mounted on the upper end of hollow stem 76 the bore of which communicates with a plurality of passageways 77 extending through the body of plug valve 75 to the upper surface thereof. The lower end of stem 76 carries a piston 78 slidably mounted in a piston chamber 79. A coil spring 80 is mounted in compression between the lower end of piston 78 and the bottom wall of piston chamber 79 and is adapted to normally urge the piston in the upward direction. A stuffing box 81 on the upper end of piston chamber 79 forms a fluid tight seal about stem 76. Piston 78 and the bottom wall of piston chamber 79 are provided with leak ports 82 and 83, respectively. A passageway 84 provides communication between the bore of stem 76 and the exterior thereof and is so positioned in the stem that it is enclosed within stuffing box 81 when the piston and stem are in their upwardly extended position, as shown in solid lines in Fig. 5, and is in communication with the interior of piston chamber 79 when the piston is in the retracted position, as shown in broken lines in Fig. 5. A pipe 85, connected to a suitable high pressure water supply (not shown), communicates with the interior of piston chamber 79 above piston 78 and is fitted with conventional solenoid operated valve 86 adapted to be opened and closed by means of a solenoid 87, connected by a pair of leads 88, 89 to a normally open switch 90. A current source 91 is connected into lead 88. Switch 90 is controlled by a relay 92 which is connected by leads 93, 94 to program clock mechanism 66.

The above described apparatus is employed to obtain automatically a continuous radio-activity log of a well in the following manner. The radiation detector 50 is disposed relative to the end of the screen 95 of a shale shaker so that the cuttings discharging from the lower end of the screen will fall through a hopper 96 controlled by an electrically operated diversion valve 97 suitably actuated by relay 70 through leads 93 and A. C. supply 74. The cuttings will pass through hopper 96 and fall into mouth 53 of tube 52 out of the path of the light beam passing between light source 67 and photo-electric cell 68. Plug valve 75 will be in the closed position against the lower end of tube 52 and the tube will fill with cuttings until a level is reached, as indicated by the broken line 96a, at which the light beam from source 67 will be interrupted. The circuit in amplifier 69 is so arranged that upon interruption of the light beam, relay 70 will be energized to close switch 71 connecting program clock mechanism 66 to alternating current source 74 starting the cycle of the clock mechanism. At the same time diversion valve 97 will be moved to the position shown in broken lines, temporarily diverting the cuttings from tube 52. Starting of the program clock cycle will first energize relay 65 to close switch 64, whereupon the impulses from radiation detector 50 will begin flowing to frequency meter 61 and thence to drive pen arm 62 of recorder 63. After lapse of a suitable time interval, as set in the program clock mechanism, sufficient to obtain the desired record of the radioactivity of the sample of cuttings collected in tube 52, program clock mechanism 66 next energizes relay 92, closing switch 90 thereby energizing solenoid 87 to open valve 86. Opening of the latter admits a

stream of high pressure water through pipe 85 into the upper portion of piston chamber 79, where the water pressure forces piston 78 downwardly against the pressure of coil spring 80 and pulls plug valve 75 downwardly and opens the lower end of tube 52. The collected cuttings will then fall out of the tube to clear it for the reception of a succeeding sample of the cuttings. As stem 76 moves downwardly under the pressure of the water, passageway 84 moves down into the interior of piston chamber 79. Water will then flow through passageway 84 into the bore of stem 76 and thence through passageways 77 which will emit jets of water under sufficient pressure to clear tube 52 and the surface of plug valve 75 of any remaining cuttings particles. Program clock mechanism 66 then completes its cycle and initial conditions are restored. At the same time communication is restored between light source 67 and photoelectric cell 68, whereupon the circuit of amplifier 69 reopens switch 71 and opens diversion valve 97, returning the stream of cuttings to tube 52. The temporary diversion of cuttings during the relatively short intervals occupied by the cycles of the program clock mechanism will not significantly affect the continuity value of the log obtained by this apparatus.

Chart recorder 63 may be of the form disclosed in Hayward U. S. Patent No. 2,404,132 issued July 16, 1946 for Apparatus for Use in Logging Wells, so that the curve of radio-activity traced on the chart by means of pen arm 62 will be automatically correlated with the depth of the well to produce directly the desired radio-activity log of the well.

It will be understood that various changes and alterations may be made in the method and apparatus heretofore described without departing from the scope of the appended claims but within the spirit of this invention.

What I claim and desire to secure by Letters Patent is:

1. In the drilling of a well by the rotary method employing a circulating stream of drilling fluid, the method of logging the well, comprising, separating from the stream of returning drilling fluid the formation cuttings in the order in which they are deposited in said stream by the drill, and measuring the radio-activity of the so separated cuttings.

2. In the drilling of a well by the rotary method employing a circulatory stream of drilling fluid, the method of logging the well, comprising, separating from the stream of returning drilling fluid the formation cuttings in the order in which they are deposited in said stream by the drill, correlating the successive groups of separated cuttings with the depths of the formations from which they came, and measuring the radio-activity of the so-separated cuttings.

3. In the drilling of a well by the rotary method employing a circulating stream of drilling fluid, the method of logging the well, comprising, passing the entire stream of returning drilling fluid through a screen to separate from the stream all of the formation cuttings in the order in which they are deposited in said stream by the drill, correlating the successive groups of separated cuttings with the depths of the formations from which they came, and measuring the radio-activity of the so-separated cuttings.

4. In the drilling of a well by the rotary method employing a circulating stream of drilling fluid, the method of logging the well, comprising, continuously diverting from the returning stream of

drilling fluid a portion thereof together with the formation cuttings carried thereby, continuously separating from said diverted portion said formation cuttings in the order in which they are deposited in said stream by the drill, continuously correlating the successive groups of separated cuttings with the depths of the formations from which they came, and measuring the radio-activity of the so-separated cuttings.

5. In the drilling of a well by the rotary method employing a circulating stream of drilling fluid, the method of logging the well, comprising, continuously diverting from the returning stream of drilling fluid a portion thereof together with the formation cuttings carried thereby, continuously separating from said diverted portion said formation cuttings in the order in which they are deposited in said stream by the drill, continuously correlating the successive groups of separated cuttings with the depths of the formations from which they came, measuring the radio-activity of the separated cuttings, thereafter remixing said diverted portion of said stream with the remainder of said stream, separating said formation cuttings from the entire re-mixed stream, and returning the stream to the well.

6. In the drilling of a well by the rotary method employing a circulating stream of drilling fluid, the method of logging the well, comprising, separating from the stream of returning drilling fluid the formation cuttings in the order in which they are deposited in said stream by the drill, measuring the radio-activity of the so-separated cuttings, and returning to the well only drilling fluid from which said cuttings have been removed.

7. In the drilling of a well by the rotary method employing a circulating stream of drilling fluid, the method of logging the well, comprising, separating from the stream of returning drilling fluid the formation cuttings in the order in which they are deposited in said stream by the drill, correlating the successive groups of separated cuttings with the depths of the formations from which they came, measuring the radio-activity of the so-separated cuttings, and returning to the well only drilling fluid from which said cuttings have been removed.

8. In the drilling of a well by the rotary method wherein a stream of drilling fluid is circulated through the well and cuttings particles of the earth formations traversed by the bit are continuously introduced into said fluid in the order in which the bit traverses said earth formations

during the drilling operation, the method of logging the well, comprising, continuously separating from successive increments of the exiting stream of said fluid cuttings particles as successively deposited therein by the bit, and measuring the radio-activity of the so-separated cuttings particles.

9. In the drilling of a well by the rotary method wherein a stream of drilling fluid is circulated through the well and cuttings particles of the earth formations traversed by the bit are continuously introduced into said fluid in the order in which the bit traverses said earth formations during the drilling operation, the method of logging the well, comprising, continuously correlating the successive increments of the exiting stream of said fluid and their contained cuttings particles with the depths of the formations to which they relate, continuously separating from said successive increments said cuttings particles, and measuring the radio-activity of the so-separated cuttings particles.

10. In the drilling of wells by the rotary method wherein a stream of drilling fluid is circulated through the well and cuttings particles of the earth formations traversed by the bit are continuously introduced into said fluid in the order in which the bit traverses said earth formations during the drilling operation, the method of logging the well, comprising, continuously correlating the successive increments of the exiting stream of said fluid and their contained cuttings particles with the depths of the formations to which they relate, continuously separating from said successive increments said cuttings particles, measuring the radio-activity of the so-separated cuttings particles, and returning to the well only drilling fluid from which said cuttings particles have been removed.
